UNITED STATES PATENT OFFICE.

OLIVE D. CORNELL, OF NEW YORK, N. Y.

BUST REDUCER AND SUPPORTER.

No. 870,226.

Specification of Letters Patent.

Patented Nov. 5, 1907.

Application filed February 16, 1907. Serial No. 357,692.

To all whom it may concern:

Be it known that I, OLIVE D. CORNELL, a citizen of the United States, and residing at New York, in the county of New York and State of New York, have invented certain new and useful Improvements in Bust Reducers and Supporters, of which the following is a specification, such as will enable those skilled in the art to which it appertains to make and use the same.

This invention relates to means for reducing and supporting the female bust, and the object thereof is to provide an improved device or garment of this class particularly designed for use by stout women, and also particularly designed to be worn over a corset but which may, if desired, be worn by more slender women

15 and also under the corset.

The invention is fully disclosed in the following specification, of which the accompanying drawing forms a part, in which the separate parts of my improvement are designated by suitable reference characters

20 in each of the views, and in which;—

Figure 1, is a front perspective view of the body portion of a woman and showing the method of wearing my improved bust reducer and supporter; Fig. 2 a side view; and, Fig. 3 a plan view of the bust reducer and 25 supporter detached.

My improved bust reducer and supporter is shown at *a* in Fig. 3 and comprises an oblong strip of any suitable fabric or flexible material, the top edge *a*² of which is straight, the ends *a*³ parallel, and the bottom edge *a*⁴ 30 curved as shown in the drawing, and the top edge *a*² is provided with straps *d* which are passed over the shoulders and which help to support the garment or bust reducer and supporter in proper position.

In practice, the ends *a*³ are provided with fastening 35 devices which may be ordinary hooks and eyes as shown at *b* and *c*, or may consist of buttons and button-holes or any other suitable fastening devices, and when the bust reducer and supporter is applied to the body as shown in Figs. 1 and 2 the ends thereof are secured 40 centrally and vertically of the breast as shown in Fig. 1.

The dimensions of my improved bust reducer and supporter are determined as follows. A measuring tape is passed around the body directly under the arms so as to determine the bust measurement along the top 45 edge line *a*² of the garment as shown in Figs. 1 and 2. The vertical width of the garment at the back, as indicated by the line *a*⁵ in Fig. 3, is determined by measuring from the line fixed as above downwardly to within about two inches of the waist line, and the vertical 50 width of the end portions *a*³ is determined by measuring from the first mentioned bust measurement centrally of the breast downwardly to a point about two inches above the waist line. This measurement will, as a general rule, make the opposite end portions of the

55 garment about twice as wide as the central back portion thereof, and the curve of the bottom line or edge *a*⁴ of

the garment will depend on the dimensions or size of the breast or bust below the line *a*², and where the breasts or bust below said line are of unusual size the curve of the bottom line *a*⁴ adjacent to the ends *a*³ may 60 be enlarged as indicated by the dotted lines *a*⁶.

The bottom edge of the garment is also provided with an ordinary draw cord or shirring tape *e*, and the longitudinal dimensions of the top edge *a*² of the garment should be such that when the ends *a*³ are fastened over 65 the breasts or bust as shown in Fig. 1, the said top edge will tightly fit around the body and draw the breasts together, and after the ends *a*³ have been connected, the draw cord or shirring tape *e* is drawn tightly around the body beneath the bust and securely tied as indicated at *f* in Fig. 1, and in this operation the bottom edge portions of the garment adjacent to the ends thereof are shirred or gathered together as shown at *g* 70 so that the bottom edge of the garment will fit snugly and evenly at the sides and back.

75

My improved bust reducer and supporter is particularly designed for use in connection with the low cut corsets now in use, and as hereinbefore stated the said device is also particularly designed for use by women of robust form and large body and bust development, 80 and when properly fitted and applied in the manner described the breasts or separate side portions of the bust will be drawn together from the opposite sides and will also be supported from beneath, and the swelling or protruding of the bust and the fleshy parts of the 85 body under the arms and at the back over the top edge of the corset will be prevented, and the entire body above the corset and particularly the bust will be securely and compactly held and any lateral or vertical movement of the breast occasioned by walking or any 90 other kind of exercise will be avoided together with the disagreeable effects thereof.

In determining the length measurement of my improved bust reducer and supporter care should be taken to determine the exact measurement around the body 95 beneath the arm-pits and the said top measurement of the garment should be such that when the end portions thereof are connected centrally of the bust as shown in Fig. 1, the breasts or separate side portions of the bust will be tightly drawn together from the side and firmly 100 supported around the mid-line of the end portions of the garment so that when the ends of the cord or shirring tape *e* are drawn tightly together and tied as shown in Fig. 1, the entire garment will fit snugly and tight at all points, and in placing the garment on the body 105 as hereinbefore described the top edge portion thereof at the front should be drawn up in the direction of the neck, as indicated both in Fig. 1 and Fig. 2, in order that the desired effects hereinbefore set out may be fully accomplished.

110

With my improved garment or bust reducer and supporter the fleshy parts of the body at the front sides and

back are securely confined and compressed above the corset and any lateral or vertical movement thereof in walking, riding or taking any other form of physical exercise is largely and, in fact, almost totally avoided, 5 and although my improvement is particularly designed for use in connection with low cut corsets the same may be worn in connection with any kind or class of corset and may also be worn without a corset, if desired.

In the accompanying drawing, I have indicated in 10 Figs. 1 and 2, a low cut corset the bottom line of which is shown at h , and the top edge portion of which is indicated by the dotted line h^2 , and when worn with a corset of this class the top edge of the bust reducer and supporter is from two to three inches above the top edge 15 of the corset at the back and sides of the body and the central front portion of the top edge of the corset is only about from two to three inches above the corresponding bottom edge of the bust reducer and supporter, the greatest portion of the bust being contained 20 in and directly supported by my improved bust reducer and supporter as clearly indicated in Fig. 1.

My invention is not limited to any particular means 25 for forming the garment which constitutes the subject thereof or for taking the dimensions thereof, and the method herein given for taking the dimensions of said garment or any other suitable method may be followed, but in all cases the end portions a^3 of the garment should be at least approximately about twice the 25 width of the central back portion thereof and the curve

of the bottom edge a^4 of the garment as a general 730 proposition should be that shown in full lines in Fig. 3, but in cases of extra or unusual development of the breast the width of the garment adjacent to the ends thereof should be increased as indicated by the dotted lines a^6 .

35

Having fully described my invention, what I claim as new and desire to secure by Letters Patent, is:—

1. A garment of the class described adapted to be worn around the upper portion of the chest or body above the waist line, said garment consisting of an oblong flexible 40 strip having a substantially straight top edge and parallel ends provided with fastening devices, the width of the ends being greater than the width of the central back portion, and the bottom edge being curved downwardly and outwardly from the central back portion to the ends and 45 being provided with a draw cord.

2. A garment of the class described adapted to be worn around the upper portion of the chest or body above the waist line, said garment consisting of an oblong flexible strip having a substantially straight top edge and parallel ends provided with fastening devices, the width of the ends being greater than the width of the central back portion, and the bottom edge being curved downwardly and 50 outwardly from the central back portion to the ends and being provided with a draw cord, said garment being also 55 provided at the top with shoulder straps.

In testimony that I claim the foregoing as my invention I have signed my name in presence of the subscribing witnesses this 14th day of February 1907.

OLIVE D. CORNELL.
